Patented Aug. 5, 1969

214,833

LOADER FOR GARDEN TRACTOR

Anton L. Glommen, Delano, Minn. 55328

Filed Oct. 3, 1968, Ser. No. 13,832

Term of patent 14 years

Int. Cl. D12—19, 13

U.S. Cl. D14—3

FIG. 4

FIGURE 1 is a side elevational view of a loader for garden tractor with a tractor shown in dotted lines for illustrative purposes only;

FIGURE 2 is a front elevational view thereof;
FIGURE 3 is a rear elevational view thereof; and
FIGURE 4 is a top plan view thereof.

I claim:

The ornamental design for a loader for garden tractor, as shown and described.
